CLAIM

The ornamental design for a vehicle brake disc, as shown and described.

DESCRIPTION

FIG. 1 is a perspective view of the vehicle brake disc showing my design;

FIG. 2 is a top view thereof (the bottom view being a mirror image); and,

FIG. 3 is a side view thereof.

The broken lines shown in the FIGS. 1 and 2 drawing views are for illustrative purposes only and forms no part of the claimed design.
